UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed August 9, 1924. Serial No. 731,062.

To all whom it may concern:

Be it known that I, WILLIAM H. DE BUSK, a citizen of the United States, residing at Chicago, in the county of Cook and State of Illinois, have invented certain new and useful Improvements in Rail Anchors, of which the following is a specification.

My invention relates to rail anchors of the type adapted to be applied to a railroad rail in position to abut against a cross-tie or other fixed part of a track for holding the rail against movement longitudinally. It is the principal object of my invention to provide an anchor of this type comprising a new and improved form and arrangement of parts, in which a clip or jaw member having an operative grip upon the flange of a rail at one side thereof is held in position on the flange and is prevented from backing 20 transversely from the flange by an improved form of retaining device.

It is another object of my invention to provide a construction of this type in which the clip is held in position by the use of a retaining member of such a type that it can be produced cheaply and applied very quickly and easily and which shall have a positive action for holding the clip in position.

It is another object of my invention to improve devices of this type in sundry details hereinafter pointed out. The preferred means by which I have accomplished my several objects are illustrated in the accompanying drawing and are hereinafter specifically described. That which I believe to be new and desire to cover by this application is set forth in the claims.

In the drawing,—

Fig. 1 is a face view of my improved anchor in position on a rail shown in vertical section and partly broken away;

Fig. 2 is a top plan view of the parts shown in Fig. 1;

Fig. 3 is a face view of the blank from which the retaining device of the construction shown in Figs. 1 and 2 is produced, a second blank being indicated in dotted lines in nesting relation;

Fig. 4 is a view similar to Fig. 1 but showing a modified form of clip and retaining member;

Fig. 5 is a view similar to Fig. 1 but show-

ing a second modified form of clip and retaining member.

Referring to Figs. 1 and 2, 10 indicates a rail of the ordinary type, supported by a cross-tie 11. A clip 12 made from a heavy plate of steel cut out at one side to provide spaced jaws 13 and 14 is shown in position upon the flange of the rail at the right in Fig. 1, the jaws 13 and 14 being spaced at such a distance apart that the clip has a hard driving fit upon the flange such that the upper jaw 13 serves to cut a groove 15 in the upper face of the flange. The grip of the clip upon the rail is thus rendered very strong for the purpose of preventing longitudinal movement of the rail with respect to the clip, the rail being thus held effectively in position, inasmuch as the clip is applied to the rail in contact with the face of the cross-tie 11.

For holding the clip 12 in position on the flange of the rail and to prevent the clip from backing transversely from the rail, I have provided a retaining member comprising a body 16, and an arm 17 carried by the body at an angle thereto, the body being adapted to extend across underneath the rail, with the arm 17 extending longitudinally of the rail. Upon the end of the arm 17, I have provided a second arm 18 in spaced relation to the body 16. Before the application of the retaining device to the rail, the arm 18 is preferably given a slight upward bending with respect to the body 16. The retaining member is then slipped into position upon the rail and clip, with the body 16 extending across below the rail and the arm 18 resting upon the upper face of the flange of the rail, and with the arm 17 in snug and rigid contact with the outer face of the clip 12. The length of the body 16 is such that there will be an end portion extending beyond the edge of the flange at the left in Fig. 1, which end portion is to be bent over upon the upper face of the flange of the rail for forming a hook 19 as shown in Fig. 2 and as indicated by dotted lines in Fig. 1.

The application of a blow or blows upon the end of the hook at the left in Fig. 1, with preferably a weight held against the end of the retaining member at the right in said Fig. 1, serves to tighten the retaining

member upon the rail and the clip whereby the clip will be held positively against any loosening movement upon the flange.

It will be understood that the clip 12 is preferably to be made of fairly high-grade metal so as to have a very strong grip upon the rail. The retaining member, however, can be made of fairly low-grade metal which shall be comparatively easily bent into retaining position and which shall have a sufficiently low resiliency that the member may be tightened very effectively upon the rail and the clip. As indicated in Fig. 3, the retaining members 16 are so formed that a pair of them can be stamped from a single rectangular piece of metal, whereby there will be no waste material.

In the preferred form shown in Fig. 4, a clip 20 is employed formed from a heavy bar of high-grade steel bent upon itself. The retaining member, however, is the same as that above described, except that it is provided with a downwardly-bent arm 21 at a point adjacent to the edge of the flange at the left in Fig. 4, and with an upwardly-extending arm 22 formed on the end of the arm 21 by bending the strip backwardly upon itself. As is shown by dotted lines in said Fig. 4, the arm 22 stands normally in such position that it is necessary to distort the arm against the force of the resiliency of the metal for forcing the retaining member into position upon the flange, the upper end portion 23 of the arm 22 being diagonally disposed so as to have a cam action against the edge of the flange for displacing the arm 22 when the retaining member is forced upwardly into position.

The retaining member comprising the arms 21 and 22 is to be of such weight of metal and of such qualities that it will yield without breaking for permitting the member to be forced into position but that it will not yield readily and easily without the application of some little force thereto. Inasmuch as there is no force applied to the clip 20 in the direction for causing the clip to back transversely from the flange as a direct component of the force normally brought to bear upon the clip in use in the track, it will be understood that the spring structure is strong enough to hold the clip in position.

In the construction shown in Fig. 5, a clip 24 is employed, similar to the clip 20, except that it is provided with a downwardly extending lug 25 for the desired extended bearing against the cross-tie. The retaining member in this construction is similar to that of Fig. 1, having a body 26, and arms 27 and 28, except that it is made of a bar of steel in lieu of the sheet-metal form, and except that it is provided with a diagonally-disposed end portion 29 in such relation that when upward pressure is applied thereto a cam action is had against the edge

of the flange at the left in said Fig. 5 for drawing the member toward the left for tightening it upon the clip 24. A hook 30 is then formed on the end corresponding to the hook 19 above described for holding the retaining member in tightened condition.

While I prefer to employ one of the forms of construction as illustrated in the drawing and above described, it will be understood that I do not wish to restrict myself to the use of any particular form, except as the same may be hereinafter specifically claimed, inasmuch as it is evident that various changes may well be made in the details of the construction without departing from the spirit of my invention.

What I claim as my invention is—

1. A rail anchor comprising a clip adapted to have a driving fit upon the flange at one side of a rail, and a retaining member for holding said clip from backing transversely from the rail, comprising an arm at one end of the member extending along one face of the clip and supported in position by contact with the upper face of the flange of the rail, and means at the other end portion adapted to engage, in the application of the member to the rail, around the edge of the flange at that side of the rail.

2. A rail anchor comprising a clip adapted to have a driving fit upon the flange at one side of a rail, and a retaining member for holding said clip from backing transversely from the rail, comprising a body, an arm carried by the body in position to extend longitudinally of the rail, means carried by the arm for supporting the member by contact with the flange of the rail, and means at the other end portion adapted to engage, in the application of the member to the rail, around the edge of the flange at that side of the rail.

3. A rail anchor comprising a clip adapted to have a driving fit upon the flange at one side of a rail, and a retaining member for holding said clip from backing transversely from the rail, comprising a body, an arm carried by the body in position to extend longitudinally of the rail, a second arm carried by said first-named arm and extending transversely of the rail into contact with the upper face of the flange of the rail for supporting the member from the flange, and means at the other end portion adapted to engage in the application of the member to the rail, around the edge of the flange at that side of the rail.

4. A rail anchor comprising a clip adapted to have a driving fit upon the flange at one side of a rail, and a retaining member for holding said clip from backing transversely from the rail, comprising a body, a hook at one end of said body operative for holding the clip in position and having contact with the flange for supporting that end of the

member from the flange, and means at the other end of the body operative by engagement with the flange at that side of the rail for holding the member normally from withdrawal from the rail.

5. A rail anchor comprising a clip adapted to have a driving fit upon the flange at one side of a rail, and a retaining member for holding said clip from backing transversely from the rail, comprising a body, a hook at one end of said body having contact with three faces of the clip for holding it in position and having contact with the upper face of the flange of the rail for supporting the 10 end of the member from the rail, and means at the other end of the body operative by engagement with the flange at that side of the rail for holding the member normally from removal from the rail.
- 15 6. A rail anchor comprising a clip adapted to have a driving fit upon the flange at one side of a rail, and a retaining member for holding said clip from backing transversely from the rail, said retaining member having 20 a substantially horizontally disposed hook at one end for engaging the clip, and a vertically disposed hook at the other end for engaging the opposite rail base flange.

- 25 7. A rail anchor comprising a clip adapted to have a driving fit upon the flange at one side of a rail, and a retaining member for holding said clip from backing transversely from the rail, comprising a body adapted to extend transversely of the rail, an arm carried by the body and extending longitudinally of the rail, means carried by the arm 30 for supporting the member by contact with

the flange of the rail, and a heavy spring arm on the other end of the member adapted by engagement with the flange at that side 40 of the rail to hold said member normally from removal from the rail.

8. A rail anchor comprising a clip adapted to have a driving fit upon the flange at one side of a rail, and a retaining member for holding said clip from backing transversely from the rail, comprising a body, means carried by the body at one end for engaging the clip for holding it in position, an arm formed integrally with the body at its other end 45 portion and depending therefrom, and a second arm formed integrally with the first-named arm and bent backwardly thereon adapted by engagement with the flange at that side of the rail to hold said member 50 normally from removal from the rail.

9. A rail anchor comprising a clip adapted to have a driving fit upon the flange at one side of a rail, and a retaining member for holding said clip from backing transversely from the rail, comprising a body, means carried by the body at one end for engaging the clip for holding it in position, an arm formed integrally with the body at its other end portion and depending therefrom, a second arm formed integrally with the first-named arm and bent backwardly thereon 55 adapted by engagement with the flange at that side of the rail to hold said member 60 normally from removal from the rail, and a diagonally-disposed cam on the upper end of said second arm for facilitating its engagement with the flange.

WILLIAM H. DE BUSK.
